UNITED STATES PATENT OFFICE.

WILFRED E. USREY, OF BINGHAM CANYON, UTAH.

DRILL-BIT.

1,324,631.

Specification of Letters Patent. Patented Dec. 9, 1919.

Application filed March 2, 1918. Serial No. 220,004.

To all whom it may concern:

Be it known that I, WILFRED E. USREY, a citizen of the United States, residing at Bingham Canyon, in the county of Salt Lake and State of Utah, have invented new and useful Improvements in Drill-Bits, of which the following is a specification.

This invention relates to drill bits and the bit hereinafter described and herein illustrated is especially adapted for use as a rock drill although it may be used for other purposes.

By reason of the construction hereinafter described, the improved bit is rendered far more durable than the ordinary bit now in common use, it being almost impossible to break or fracture the bit by reason of the disposition of the cutting faces or edges thereof.

It is a further object of the invention to produce a bit which will remain sharp for a long period of time and which may be easily re-sharpened when necessary.

It is a further object of the invention to produce a bit having an active face which is square in plan and which face is inclined or beveled from its sides and ends to the center thereof, the apex and corners of the beveled portions each presenting a separate cutting edge, the beveled surfaces presenting pulverizing faces and the sides presenting cutting surfaces whereby the rock or ore acted on during the cutting operation will be both cut and pulverized so that the bit can perform its work with great rapidity and accuracy.

With the above and other objects in view, the invention consists in the novel construction, combination and arrangement of parts as herein described, illustrated and claimed.

In the accompanying drawings,

Figure 1 is a perspective view of the improved bit.

Fig. 2 is a view looking toward the working face of the bit.

The improved bit comprises the usual shank 1 which may be of any desired diameter and length according to the use to which it is to be put. The working end of the bit 2 is enlarged as shown, to provide a head 2 which is substantially square or rectangular, comprising the four sides or edges 3.

The working face of the bit comprises a central cutting edge 4 of any suitable length, preferably of the same length as the diameter of the shank 1, and other cutting edges 5 which extend from the opposite extremities of the cutting edge 4 to the corners of the head of the bit. Thus five cutting edges 6, 60 said cutting edges being approximately equal in length. By such formation and arrangement of the cutting edges 4 and 5, inclined crushing or pulverizing faces 6 and 7 being formed, there being four of such inclined faces, the faces 7 being hatched at greater angles than the faces 6. By reason of the faces 6 and 7 the bit operates to pulverize the rock or ore simultaneously with the cutting operation.

I claim:

A rock drilling bit comprising a shank which is flared outwardly at one of its ends to provide four angular walls and straight edges at the ends of the walls, said bit, from the said straight edges being extended outwardly and the said extensions being beveled inwardly to provide a sharpened edge which is of a length approximately equaling the cross sectional diameter of the shank so that two of the diametrically opposed beveled walls are of a greater angular pitch than the remaining two beveled sides.

In testimony whereof I affix my signature.

WILFRED E. USREY.
